UNITED STATES PATENT OFFICE.

JOHN E. DEARDORFF, OF VISTA, CALIFORNIA.

ADOBE WALL CONSTRUCTION.

Application filed November 23, 1926. Serial No. 150,173.

This invention relates to an adobe wall construction. The general object of the invention is to produce a wall construction of this character in which the bricks can be readily 5 laid in courses, and in which the bricks in the wall will be bonded together so as to produce a rigid and strong wall; also to provide a construction for the wall which will operate to hold stucco or plastering securely on the wall 10 and also which will facilitate the laying of the bricks against the side of a door frame, so as to enable them to hold the door frame securely in the wall.

A further object of the invention is to provide 15 a construction for such a wall which will enable the adjacent bricks of a course to be bonded together and at the same time laid so that they present an end space between the bricks which can receive stucco when applied 20 to the face of the wall.

A further object of the invention is to produce an adobe brick having a special construction facilitating its being bonded when laid into a wall, and facilitating the application 25 and securing of stucco and mortar to the exposed faces of the brick.

Further objects of the invention will appear hereinafter.

The invention consists in the novel parts 30 and combination of parts to be described hereinafter, all of which contribute to produce an efficient adobe wall construction.

A preferred embodiment of the invention is described in the following specification, 35 while the broad scope of the invention is pointed out in the appended claims.

Figure 1 is a side elevation of an adobe wall construction embodying my invention, broken away and illustrating a part of a door 40 frame; this view shows a part of the wall in elevation and a part of the wall in section, as though the stucco had been removed, the remainder of the wall being shown in vertical section passing through the bodies of the 45 bricks.

Figure 2 is a vertical section through the wall taken about on the line 2—2 of Fig. 1.

Figure 3 is a horizontal section through the wall, taken about on the level of the line 3—3 50 and passing completely through the opposite sides of the door frame so as to show portions of the wall contiguous to the door frame at each side.

Figure 4 is a perspective of one of the adobe 55 bricks.

In practicing the invention, I prefer to

form adobe bricks of a thickness to correspond with the desired thickness of the wall, that is to say, the wall has a thickness the width of the brick. The brick preferably has 60 a length equal to twice the thickness of the wall, for example, in a twelve-inch wall I employ an adobe brick of two feet in length.

In Figure 4 I illustrate the preferred form of the adobe brick. In this view, 1 represents the brick and 2 represents aligning notches which are formed in the end faces of the brick. The end faces are plane, and simply abut against each other. Embedded 65 in the brick, I provide a wire mesh or gauze 70 3 which is in the form of a sheet located in a plane substantially parallel with the plane of the large faces of the brick. This sheet is preferably in the middle plane of the brick, extends across the notches and projects beyond 75 the side edges 4 of the brick at each side. The notches 2 extend completely through the brick.

In laying the brick to form a wall 5 (see Fig. 1), the bricks are laid in courses 6, one upon the other, in the usual way in laying bricks, but I do not provide any mortar between the adjacent end faces 7 of the bricks (see Fig. 3). However, the bricks are laid in mortar 8 between the horizontal courses. Furthermore, the bricks are laid so that the two adjacent courses "break joints" with respect to each other. As each course of bricks is laid, I bond the adjacent bricks together at their ends by placing a filler 9 of mud or similar material into the aligning notches 80 (see Fig. 3). The filler embeds the wire mesh which crosses these notches, and securely bonds the bricks together. It prevents any relative lateral movement of the bricks. 85 Hence the ends of the bricks may be made plane and devoid of any projections.

I employ the projecting portions of the wire mesh to produce the effect of laths for assisting in securing stucco 10 on the outer face of the wall and plaster 11 on the inner face. Fig. 2 illustrates the manner in which these projecting portions of the gauze sheet 3 are utilized in this respect. I prefer to bend these projecting portions downwardly, as indicated, and in such a way that when the plaster or stucco is applied, the mesh is embedded in the same and operates as lath to hold the stucco and plaster on the face of the wall. By reason of the end spaces 7 between the end faces of the brick in each course, a space is provided into which the 90 95 100 105 110

stucco and plaster protrude, as indicated at 12 in Fig. 3. These spaces of course only extend through the height of each course, so that these spaces also assist materially in 5 securing the stucco and plaster on the face of the wall. They effectively prevent lateral shifting of the stucco and cooperate with the wire mesh to hold the stucco and plaster very securely on the face of the wall.

10 Where it is necessary to build a door frame, such as the door frame 13, in the wall, I provide the door frame with a vertical cleat 14 (see Fig. 3). This cleat has a cross section which will enable it to fit in the notches 2. 15 The bricks which are laid against this door frame will have the wire gauze cut out of the notches so as to enable them to be laid snugly against the door frame, as indicated.

It is understood that the embodiment of 20 the invention described herein is only one of the many embodiments this invention may take, and I do not wish to be limited in the practice of the invention, nor in the claims, to the particular embodiment set forth.

25 What I claim is:—

1. In a wall construction, the combination of a plurality of bricks laid in courses, said bricks having aligning notches extending completely through the bricks at their adjacent ends, and having wire mesh sheet embedded in a substantially horizontal plane in the bricks substantially parallel with the plane of the large side faces of the brick, extending across the said notches, and a filler 35 of bonding material received in the aligning notches to bond the adjacent bricks together.

2. In an adobe wall construction, the combination of a plurality of bricks laid in courses end to end and having aligning notches on 40 their adjacent end faces, said bricks having wire mesh in the form of horizontal sheets embedded therein extending across the notches and having edges projecting beyond the side face of the wall, a bonding filter received in the abutting recesses, and stucco covering the face of the wall and embedding the projecting edges of the wire mesh.

3. In an adobe wall construction, the com-

bination of a plurality of bricks laid in courses, the adjacent ends of the bricks of each course having aligning notches in their adjacent ends, wire mesh in the form of horizontal sheets embedded in the bricks and extending across the notches, a filler of bonding material received in the notches and embedding the wire mesh in the notches to bond the adjacent bricks of a course together, the end faces of adjacent bricks in a course being disposed slightly apart to form end spaces 55 between the bricks, said wire mesh having edges projecting beyond the side face of the wall, and stucco covering the wall, embedding the projecting wire mesh and protruding into the said end spaces between the bricks.

4. In an adobe wall construction, the combination of a plurality of bricks laid in courses and having notches in their adjacent end faces, the bricks of each course being disposed slightly apart so as to form an end space between the ends of adjacent bricks, 60 said bricks having wire gauze in the form of substantially horizontal sheets embedded therein and having edges projecting beyond the faces of the bricks on each side of the wall, 65 said wire gauze also extending across the said notches, fillers of bonding material received in the said notches and bonding together adjacent bricks of each course, stucco on the outer face of the wall embedding the projecting edges of the wire gauze and extending into the said end spaces, and plaster on the inner face of the wall embedding the projecting wire gauze and extending into the said 70 end spaces.

5. An adobe brick having notches in its 75 ends extending completely through the brick and having wire gauze embedded in the same and extending across the said notches.

6. An adobe brick having notches in its end faces extending completely through the brick 80 and having wire gauze embedded in the body of the brick and with the gauze extending beyond the side edges of the brick.

Signed this 6th day of November, 1926.

JOHN E. DEARDORFF.
